United States Patent Office

Des. 181,990
Patented Jan. 28, 1958

181,990

HEADBOARD OR THE LIKE

John J. Lubberts and Lambert J. Mulder, Grand Rapids, Mich., assignors to Tomlinson of High Point, High Point, N. C., a corporation of North Carolina

Application April 16, 1957, Serial No. 45,757

Term of patent 14 years

(Cl. D5—4)

FIG. 1

We claim:

The ornamental design for a headboard or the like, substantially as shown.
